UNITED STATES PATENT OFFICE.

JAMES A. MULHERIN, OF ST. LOUIS, MISSOURI, ASSIGNOR, BY DIRECT AND MESNE ASSIGNMENTS, TO HENRY DELKESKAMP, OF ST. LOUIS, MISSOURI.

COMPOSITION SHOE HEEL AND METHOD OF MAKING THE SAME.

Application filed August 1, 1921. Serial No. 488,974.

This invention relates to shoe heels, and more particularly to heels of the composition type.

One of the objects of this invention is to provide a shoe heel which possesses the required strength, which can be readily attached to the shoe, which is adapted to receive a high finish, and to which the leather of the shoe sole can be readily attached.

Another object of this invention is to provide a process or method for making such a heel.

Further objects will appear from the detail description taken in connection with the accompanying drawing in which the figure is a cross-section of a shoe heel embodying this invention.

The shoe heel embodying this invention comprises a body 1 of plastic material and a coating 2 which is combined therewith to form a composite mass. In the case of high heels, a core 3 is provided in order to secure the desired strength and this core extends from the seat to the tread. The core is formed of wood or any other suitable material which is adapted to be penetrated by a fastener, such as a nail or a screw. The body 1 is a rubber composition and is preferably formed of a ligneous material which is mixed and vulcanized with the rubber.

In the particular embodiment of this invention the body comprises saw-dust, cork and raw rubber in the proportion of about seventy-five per cent (75%) of saw-dust, five per cent (5%) of cork and twenty per cent (20%) of raw rubber. The coating 2 is of hard rubber which is vulcanized on the body.

In accordance with the process embodying this invention the saw-dust, cork and raw rubber are mixed and placed in a mold around the core and the body is then molded under pressure while subjected to a vulcanizing heat. This may be accomplished in any suitable vulcanizing mold which, as usual, may be heated by steam. It will, of course, be understood that a suitable amount of sulphur may be added to the mixture to secure proper vulcanization of the body.

The body being formed to shape is now coated with a layer of hard rubber; this may be accomplished by forming a hard rubber sheet (made in accordance with any suitable hard rubber formula) around the formed body; the coated body is then placed

in a mold and again subjected to pressure at a vulcanizing heat, whereby the coating will not only run together to form a continuous surface covering but will also combine with the body to form a composite mass.

Where the heel is provided with a top lift 4 which may be attached to the body by any suitable fastener, such as a nail 5 driven into the core, it will be unnecessary to coat the body tread; furthermore it will be unnecessary to coat the seat 6 of the heel. Moreover where as is often the case especially in high heels the sole is pasted against the breast 7 of the heel, it will be unnecessary to cover this breast. It will be understood, therefore, that the covering is applied to such faces as may be necessary to meet the requirements and to adapt the heel to the uses as desired.

It will, therefore, be seen that the invention accomplishes its objects. A heel is provided which is a composite mass. The body of the heel not only has great strength but the required density and lightness on account of the large proportion of saw-dust used in its manufacture. This body moreover is adapted to receive the nails or other fastening means and on account of the intimate mixture of the components of the vulcanized body and the nature of the vulcanized mixture, it is adapted to firmly retain the nails or other fastenings which may be used. In low heels, therefore, it is unnecessary to use the core since the fasteners may be driven directly into the composite vulcanized heel body. Moreover the body is of such a nature that it will readily take cement. Accordingly the heel can be conveniently cemented to the shoe; this characteristic is especially advantageous in that it permits the flap on the sole to be cemented against the heel breast as is usual in wooden heel constructions. The coating not only forms a hard protective covering but also one which is adapted to receive a high polish and presents a neat appearance.

It will be noted that the core 3 terminates a short distance below the seat of the heel thereby providing an open recess 8. This makes the structure resilient since the body will give slightly when the weight of the foot comes on the heel, which resiliency is desirable in heel constructions.

It is obvious that various changes may be made in details of construction without

departing from the spirit of this invention; it is, therefore, to be understood that this invention is not to be limited to the specific details shown and described.

5 Having thus described the invention, what is claimed is:

1. A shoe heel, comprising, a vulcanized mixture of sawdust, cork and rubber.

10 2. A shoe heel, comprising, a body of plastic material having a core extending from its seat to its tread, and a coating combined therewith to form a composite mass.

15 3. A shoe heel, comprising, a core, and a composition body of rubber and granular material vulcanized on said core.

4. A shoe heel, comprising, a core, a body of rubber composition vulcanized on said

core, and a coating of rubber vulcanized on said body.

5. In the art of making shoe heels, the 20 process comprising, molding a body of plastic material, coating the body with hard rubber, and molding the coated body while subjected to a vulcanizing heat.

25 6. In the art of making shoe heels, the process comprising, molding a body of plastic material while subjected to a vulcanizing heat, coating the body with hard rubber, and molding the coated body while subjected to a vulcanizing heat.

30 In testimony whereof I affix my signature this 19th day of July, 1921.

JAMES A. MULHERIN.
